ABSTRACT OF THE DISCLOSURE

A stamping device comprising a squeeze container having an applicator disposed in its neck. The applicator has a web provided with a valve opening therethrough. A valve member is disposed in the opening and engages the web for closing the opening. A retainer ring provided with a fabric cover forms part of the applicator. A duplicating stencil is disposed over said cover and a cap having an opening therethrough is secured to said container with said cover at least under slight compression so that at least a portion of said stencil sheet protrudes beyond said cap.

This invention relates to a stamping device and has for an object the provision of means for controlling flow of ink or other duplicating fluid from a squeeze container to a stencil sheet in a manner to insure optimum reproduction of the stencilled material, and in which the stencil sheet is readily replaceable.

Briefly, the concept of this invention contemplates a stamping device comprising a squeeze container having a neck portion. A body is received in the neck portion and has a web provided with a valve opening therethrough. A valve member is disposed in the opening and is engageable with the web for closing the opening. The body further includes a retainer ring having a flange. A fabric cover is secured to the retainer ring outwardly of the container. A duplicating stencil sheet is disposed over the cover and a cap having an opening therethrough is secured to the container with the cover at least under slight compression so that at least a portion of the stencil sheet protrudes beyond the cap.

A further object of the invention resides in the provision of a normally closed valve structure for the stamping device including resilient means on both sides of the valve seat for urging the valve closed thus insuring optimum control and safe guard against spillage.

Another object of the invention resides in the use of a valve member for an applicator which is movably mounted with respect to the valve seat yet which is locked against accidental displacement from the applicator.

Still further objects of this invention reside in the provision of a stamping device especially adapted for dating documents, for use by postal officials, for indicating payment or receipt of bills, invoices or like documents, which is exceedingly easy to use, inexpensive to manufacture, and which is substantially foolproof.

These, together with the various ancillary objects and features of this invention, which will become apparent as the following description proceeds, are attained by this stamping device, preferred embodiments of which are illustrated in the accompanying drawings, by way of example only, wherein:

FIG. 1 is a perspective view of a stamping device constructed in accordance with the concepts of the present invention;

FIG. 2 is an enlarged vertical sectional view taken along the plane of line 2—2 in FIG. 1;

FIG. 3 is a view similar to FIG. 2 showing the stamping device in use and with the valve in an open position;

FIG. 4 is a schematic view illustrating the manner in which the valve assembly is formed;

2

FIG. 5 is an enlarged sectional detail view taken along the plane of line 5—5 in FIG. 2 illustrating the construction of the cover; and

FIG. 6 is a sectional detail view illustrating a modified form of the invention.

With continuing reference to the accompanying drawing, wherein like reference numerals designate similar parts throughout the various views, reference numeral 10 is used to generally designate a stamping device according to the present invention. The stamping device 10 includes three main parts; a squeeze container 12, an applicator 14, and a cap 16.

The squeeze container 12 is made from polyethylene, polyurethane or other similar synthetic plastic material and may be of any suitable shape and is provided with a neck 18 having external threads 20. The container is adapted to be filled with a duplicating fluid such as conventional stencil ink, or when the device is used with hectographing material a spirit fluid such as alcohol or the like.

The applicator 14 is adapted to be mounted in the container 12 and includes a body 22 of generally cylindrical shape which projects into the neck 18. Integrally formed with the body 22 is a web 24 having a tapered opening 24a therein which opening is larger at the top than its bottom. Integrally formed with the web 24 is a retaining ring which includes an outer flange 26 as well as an inner flange 28. The outer flange 26 is swaged over a two-ply fabric cover 30, the construction of which can be seen best in FIG. 5 and which includes a lower layer 32 of ink absorbent material such as felt or the like, and an upper layer 34 of a porous fabric such as woven cotton or the like. The cover 30 is adapted to abut against a stencil sheet 36 which is held in place by the cap 16. The cap includes a downwardly projecting cylindrical portion 38 having internal threads 40, which are threadedly engaged with the threads 20 of the bottle, and when the cap is rotated, draw the cap 16 downwardly over the applicator 14.

Integrally formed with the web 24 is a retaining ring which includes an outer flange 26 as well as an inner flange 28. The outer flange 26 is swaged over a two-ply fabric cover 30, the construction of which can be seen best in FIG. 5 and which includes a lower layer 32 of ink absorbent material such as felt or the like, and an upper layer 34 of a porous fabric such as woven cotton or the like. The cover 30 is adapted to abut against a stencil sheet 36 which is held in place by the cap 16. The cap includes a downwardly projecting cylindrical portion 38 having internal threads 40, which are threadedly engaged with the threads 20 of the bottle, and when the cap is rotated, draw the cap 16 downwardly over the applicator 14.

The side walls of the cap are knurled as at 42 for facilitating the rotation thereof. The top 44 of the cap is provided with an opening 46 therein through which the stencil sheet 36 and the cover 30 is adapted to project. Disposed between the web 24 and the cover 30 is a compressible body 47 formed of a porous foamed plastic or sponge-like material. Because the body 47 is under compression, it will tend to move the cover and the stencil sheet 36 upwardly through the opening 46 and when the cap 16 is screwed down tightly, the top of the stencil sheet 36 assumes a substantially flat position whereby an impression made on the stencil sheet can be transferred to any suitable surface.

The applicator further includes a valve member 48, which has a valve head 50 which is outwardly curved and flared and so arranged that the peripheral edge 51 is adapted to engage the valve seat 24a to form a tight fluid seal. The valve head 50 is integrally formed with a plate 53 which is integrally interconnected with the ring 52 by means of three flexible resilient helical springs 54 integrally molded as a part of the valve member 48. The springs 54 are under continuous tension thus urging the valve head 50 continuously toward engagement with the valve seat 24a. The ring 52 sits in a shoulder 56 formed in the lower end of the body 22.

The valve member 48 cannot fall free of the applicator because during the manufacture of the valve member and its installation in place, the tubular portion 58 of the valve head 50 as defined by a central opening 60 is flared outwardly by use of a tool 62 provided with a conical head 64. The tool is preferably heated and when applied causes the valve head to achieve the flared shape as shown in FIG. 2.

In use, a stencil disc or sheet has typed thereon any

suitable indicia such as the date shown on the stencil sheet 36 in FIG. 1. Then, the stencil sheet is inserted into the cap and the cap screwed down after which merely squeezing the container 12 as shown by the arrows in FIG. 3 will cause pressure on the plate 53 and the valve head 50 to open the valve head and permit fluid flow in the direction of the arrows in FIG. 3. A suitable amount of ink or duplicating fluid will be metered to the stencil sheet 36 and the date or other indicia on the stencil 36 will be transferred to the document or other suitable surface as desired.

In FIG. 6 there is shown a modified form of the invention in which the neck 66 of a container is provided with an outwardly turned lip 68 so that the cover 70 which has a downwardly and inwardly extending flange 72 may be snap-fitted in place in lieu of being threadedly secured. This form of the invention functions otherwise in the same manner as the embodiment shown in FIGS. 1 through 5.

A latitude of modification, change and substitution is intended in the foregoing disclosure, and in some instances some features of the invention will be employed without a corresponding use of other features. Accordingly, it is appropriate that the appended claims be construed broadly and in a manner consistent with the spirit and scope of the invention herein.

I claim:

1. A stamping device comprising a squeeze container having a neck portion, duplicating fluid in said container, a body received in said neck portion and having a web 30 provided with a valve opening therethrough, a valve member disposed in said opening and engageable with said web for closing said opening, said body including a retainer ring having a flange, a fabric cover secured to said retainer ring outwardly of said container, a duplicating 35 stencil sheet disposed over said cover, a cap having an opening therethrough, and means securing said cap to said container with said cover at least under slight compression so that at least a portion of said stencil sheet protrudes beyond said cap.

40 220—55.3

2. A stamping device according to claim 1, wherein valve member includes an outwardly flared resilient valve head, said opening being tapered forming a valve seat, said valve member including spring means below said web integral with said valve head drawing said valve head into resilient engagement with said valve seat.

5 3. A stamping device according to claim 2, wherein said valve member includes plate means spaced from said web so that upon application of pressure on said squeeze container fluid pressure on said plate means will open valve member.

4. A stamping device according to claim 3, wherein said spring means includes a plurality of spaced helical spring members under tension.

5. A stamping device according to claim 4, including a resilient body under compression disposed between said web and said cover and normally urging said valve head against said valve seat.

6. A stamping device according to claim 5, wherein said cap is threadedly secured to said container.

7. A stamping device according to claim 1, wherein said cap is threadedly secured to said container, and means engaging said cover under compression forcing said cover through the opening in said cap with said portion being substantially flat across its top.

8. A stamping device according to claim 1, wherein said cap is snap fitted to said container.
